(No Model.)

G. A. WELLES, Jr.
ARMATURE FOR DYNAMOS AND MOTORS.

No. 555,628.

Patented Mar. 3, 1896.

UNITED STATES PATENT OFFICE.

GEORGE A. WELLES, JR., OF NEW YORK, N. Y., ASSIGNOR TO THE C. & C. ELECTRIC COMPANY, OF NEW JERSEY.

ARMATURE FOR DYNAMOS AND MOTORS.

SPECIFICATION forming part of Letters Patent No. 555,628, dated March 3, 1896.

Application filed April 12, 1895. Serial No. 545,437. (No model.)

To all whom it may concern:

Be it known that I, GEORGE A. WELLES, Jr., of the city, county, and State of New York, have invented a certain new and useful Improvement in the Construction of Armatures for Dynamos and Motors, of which the following is a full description.

The accompanying drawings illustrate the invention, of which—

10 Figure 1 is a vertical side view of the armature complete having a section broken away. Fig. 2 is a view of this section; Fig. 3, a peripheral view of the armature, part of it containing the winding and the other part showing the place upon which the coils are wound.

15 The body of the armature consists of a series of thin plates A, insulated from each other and bolted together in segments, which when assembled and brought together end for end

20 form the body of the armature-ring. The plates constituting these segments are of equal length; but when brought together they are alternately arranged so that one plate projects from the end and the next recedes, so that an 25 adjoining segment corresponding in form will fit into the openings thus left and unite there- with to make a compact ring.

The plate a' surrounds the armature on one side and the plate a² on the other side and are 30 secured by insulated bolts which pass through the series of thin plates A, and around them all is placed the coil D of the armature. These plates a' a² are also formed in segments and rabbeted at their ends to overlap and make 35 a continuous surface when in place.

In constructing this armature the thin plates a' a² are first put together, as above described, in as many segments of a circle as may be desired. Upon a form or bobbin cor- 40 responding in section with the armature-body the coils are wound by suitable machinery or by hand, then removed from this form and slipped over the segments of the armature until these segments are suitably provided 45 with coils. They are then assembled and secured as hereinafter described.

In winding the armature as above de- 50 scribed it will be seen that owing to the differences in the diameters certain spaces or openings are left upon the outer periphery,

as shown at a⁵. These spaces serve to make a place for the fingers of the outer retaining-rings. B is one of these rings which passes around on one side of the armature, and B' is another ring for the same purpose on the opposite side, both bolted to the rings a' and a² and hold the parts rigidly together. The rings B B' are provided with fingers b⁴, which enter the open spaces a⁵ on the periphery of the armature. The ring B is also provided with bolt-holes b' to receive the bolts which secure the radial arms of a spider c'. This spider has an opening for passing over the shaft. It is split and is secured to said shaft by means of the bolt b³.

As thus constructed, it will be seen that the armature is composed of sections upon which the winding is placed and the sections then fitted to their places and the retaining-plates B and B' secured to the side, leaving the complete armature held and supported by the spider C and projecting from the plate to co-operate with the pole-pieces of a suitably-constructed magnet.

What I claim, and desire to secure by Letters Patent, is—

1. A ring-armature for a dynamo or motor built up in segmental sections and provided with coils so placed thereon that spaces are left on the outer periphery thereof, in combination with a circular retaining-ring secured at one side of said armature and provided with fingers arranged to enter said spaces, whereby the segmental sections are held and secured together.

2. A ring-armature for a dynamo or motor, built up in segmental sections, and provided with coils so placed thereon that spaces are left on the outer periphery thereof, in combination with a circular retaining-ring secured at one side of said armature and provided with fingers arranged to enter said spaces, whereby the segmental sections are held and secured, and a spider provided with radial arms secured to said retaining-ring.

3. A ring-armature for a dynamo or motor built up in segmental sections and provided with coils so placed thereon that spaces are left on the outer periphery thereof, in combination with two circular retaining-rings secured

one to each side of said armature and provided with fingers arranged to enter the spaces on the outer periphery thereof, whereby the segmental sections are held and secured radially, 5 and a spider with radial arms secured to one of said retaining-rings.

Signed at Garwood, in the county of Union

and State of New Jersey, this 11th day of April, A. D. 1895.

GEORGE A. WELLES, JR.
